UNITED STATES PATENT OFFICE.

ABRAHAM NOVICK, OF NEW YORK, N. Y., ASSIGNOR TO F. L. SCHMIDT COMPANY, OF NEW YORK, N. Y., A CORPORATION OF NEW YORK.

ENVELOP-MACHINE.

1,288,144.

specification of Letters Patent. Patented Dec. 17, 1918.

Application filed November 8, 1917. Serial No. 200,863.

To all whom it may concern:

Be it known that I, ABRAHAM Novick, a citizen of the United States, and a resident of New York, borough of Manhattan, in the county of New York and State of New York, have invented certain new and useful Improvements in Envelop-Machines, of which the following is a specification.

This invention relates to envelop machines and particularly to those portions thereof which are provided for operating upon the seal and bottom flaps of envelopes. The object of my improvements is to provide a mechanism of high efficiency at high speed for gumming and folding the bottom flap and for gumming and creasing the seal flap. My improved mechanism while of wide utility in envelop machines in general is herein illustrated as particularly adapted for operating upon envelopes commonly known as catalogue envelopes. Such envelopes are commonly provided with relatively long opposite side flaps folded over onto the body of the envelop and gummed together and with relatively short bottom and seal flaps, the first of which is folded over and gummed to the previously folded and gummed side flaps, and the latter of which is creased and may be provided with gum for sealing.

In the preferred embodiment of my improvements as herein illustrated:—

Figure 1 is a diagrammatic side elevation partly in section of so much of an envelop machine as will serve to suitably show my invention. Figs. 2 to 8 inclusive are diagrammatic side elevations, partly in section, of portions of what is shown in Fig. 1 and illustrate successive steps in the operation of my improvements. Figs. 9 and 10 are plan views of an envelop partly formed, and completed, respectively, illustrating the operation of my improvements. Figs. 2 to 8 inclusive are to one scale, larger than the scale of Fig. 1, and Figs. 9 and 10 are to another scale, smaller than the scale of Fig. 1.

In the interest of clarity, as far as possible extraneous features of the machine, such as framing, have been omitted and the showing confined to the parts directly pertaining to my improvements and to their relative movements.

Rotatable frame 2 is fixed to rotatable shaft 3 and rotatable frame 4 is adjustably fixed to said shaft. Said frame 2 carries

flap folding blade 5, one of a coacting pair of members for folding bottom flap 50, Figs. 9 and 10, and gummer 6 for supplying gum for gumming said flap to the previously folded and gummed side flaps 51, 52. 60 Frame 4 carries gummer 7 and creaser 8 for gumming and creasing, respectively, seal flap 53, Figs. 9 and 10. In their outer and operative positions gummers 6 and 7 travel in a path indicated by dot and dash circle 9. 65 Said gummers may have gum delivered to their peripheral faces by some convenient known means, not shown. Said circle 9 has a diameter equal to half the diameter of rotatable frame or cylinder 10. 70

Said cylinder 10 is fixed to shaft 15 and carries two oppositely disposed clips 11 and 12 which coact with blade 5 on frame 2. By suitable gearing not shown frames 2 and 4 are caused to make two revolutions about 75 the axis of shaft 3 for each rotation of cylinder 10 whereby clips 11 and 12 are brought successively into coaction with blade 5. Disposed above and contiguous to the field of coaction of blade 5 and clips 11 and 12 are 80 feed rolls 13 and 14 on axes fixed relatively to the axes of shafts 3 and 15. By suitable gearing, not shown, said rolls are caused to rotate in the direction of their respective arrows at a surface speed equal to the surface speed of cylinder 10. Between feed rolls 13 and 14, the usual guide plate 16 for the partly formed envelop is provided. 85

To the right of cylinder 10, Fig. 1, fixed to shaft 18, is rotatable cylinder 17, of equal diameter with cylinder 10. Said shaft 18 has its axis fixed relatively to the axes of shafts 3 and 15 and by means of gearing, not shown, cylinder 17 fixed thereon is rotated at an equal circumferential speed to that of 95 cylinder 10. Said cylinder 17 is provided with oppositely disposed clips, only one of which, clip 19, is shown, for receiving the envelop from cylinder 10.

Referring now more particularly to Figs. 100 2 and 3, fixed to shaft 20, rotatably mounted in the upper arm of bracket 30 of the machine frame, is hub 21 having fixed thereon feeler finger or blade 22. Guide plate 16 is provided with pocket 23 near the lower end 105 thereof, into which the lower end of said finger 22 is adapted to swing, said finger being normally urged thereto by spring 24. Also fixed to shaft 20 is pawl 25 for engagement with abutment 26 of gummer cam 27. 110

Said cam 27 is pivotally supported on shaft 28 fixed in the lower arm of bracket 30. Said cam is urged to engagement with stop pin 29 in bracket 30 by spring 31. For lifting, at suitable times, finger 22 from engagement with pocket 23 of plate 16, cam 32, fixed to rotatable shaft 3, is provided. Arm 33, pivoted at 35 in bracket 30, carries at its lower end roll 34 for engagement with said cam 32 and has its upper end in engagement with the under side of pin 36, fixed in hub 21 of finger 22. When said cam 32 is in the rotative position shown in Fig. 2, roll 34, urged by strong spring 37 against arm 33, passes into the depression in said cam and finger 22 is swung out from pocket 23 of plate 16 against the resistance of weak spring 24. This provides a free opening for the entrance of a partly formed envelop 54 between plate 16 and finger 22, Fig. 2. If said finger was not thus lifted the leading end of the swiftly moving envelop or blank would impinge upon said finger and unless that envelop was made of heavy paper, would be liable to mutilation.

Immediately after the leading end of the envelop passes said finger 22, cam 32 passes outwardly and roll 34 is lifted and the upper end of arm 33 withdraws from pin 36 and finger 22 is urged by spring 24 against the surface of the traveling envelop without injury thereto, Fig. 3. Said finger 22 is thereby prevented from passing into pocket 23 and pawl 25 is held out of engaging position with abutment 26 of cam 27.

Referring further particularly to Fig. 3, gummer 6 is pivotally mounted at 38 on frame 2 and is provided with roll 39 for engagement with the under face of cam 27. Said gummer 6 is urged to its outward position by spring 40 and is prevented from protruding beyond the periphery of circle 9 by arm 41 thereon in engagement with shaft 3. Spring 40 is much stronger than spring 31 of cam 27, and pawl 25 being in its lifted position, roll 39 will pass under and lift cam 27 without disturbing the peripheral position of gummer 6 and which gummer will therefore be in operative position for gumming the envelop when it rotates into engagement therewith, Fig. 6. Seal flap gummer 7 is similarly pivoted at 42 on frame 4 and is provided with roll 43 for engagement with cam 27. Frame 4 may be rotatably adjusted about shaft 3 by loosening set screw 47 whereby the peripheral location of gummer 7 and creaser 8 relatively to gummer 6 and blade 5 may be shifted to accommodate different lengths of envelopes. Said gummer 7 is urged to its outward position by strong spring 44 against stop pin 45 in frame 4.

When said roll 43 reaches the upper end of cam 27, roll 39 will have passed out of engagement with the lower end thereof

whereby said cam will be permitted to return to the position of Fig. 2 against its stop 29, but the continued presence of blank 54 between plate 16 and finger 22 will prevent pawl 25 from engaging abutment 26, whereby said roll 43 is free to lift cam 27 a second time, which by the power of strong spring 44 it will do. Gummer 7 will therefore maintain its outward position, Fig. 7. However, if finger 22 encounters no envelop when it is released by cam 32 forcing roll 34 outwardly, said finger will pass into pocket 23 of plate 16 and pawl 25 will engage abutment 26 of cam 27, thereby locking that cam in its inner position. Then when rolls 39 and 43 successively encounter cam 27 they will be forced inwardly toward shaft 3 and their respective gummers 6 and 7 will be retracted from peripheral path 9 and prevented from depositing gum on the face of cylinder 10, Figs. 1 and 4.

Blade 5 is fixed to shaft 48, oscillatably mounted in frame 2 and said shaft also has fixed thereto arm 49 carrying roll 55 for engagement with fixed cam 56. Said roll 55 is urged to engagement with cam 56 by spring 57, Figs. 5 and 6.

For successively coacting with said blade 5 for folding bottom flap 50, opposite clips 11 and 12 are provided on cylinder 10. As 95 these clips are in all particulars duplicates, a description of one will suffice for both. Clip 11 is fixed to rock shaft 58 pivoted in cylinder 10 and protrudes through an opening or break in the rim of said cylinder. 100 Also fixed to said rock shaft is arm 59 carrying roll 60 for engagement with fixed cam 61. Spring 62 is efficient for urging roll 60 to engagement with cam 61.

Said cylinder 10 is provided with means 105 for coacting with creaser 8 for creasing seal flap 53 of the envelop. Said means comprises a thin creaser table 63, lying close to the unbroken peripheral surface of cylinder 10 and extending lengthwise said cylinder 110 parallel with its axis. Said table is relatively narrow circumferentially said cylinder and may have a groove 64 lengthwise thereof for coaction with creaser 8. Said table is carried by one or more arms 65 extending radially from shaft 15 and adjustably secured to said shaft by set screws 66. By this arrangement table 63 may be adjusted circumferentially of cylinder 10 to time said table and groove 64 thereof with 115 creaser 8. Thus by adjusting frame 4, carrying creaser 8 and gummer 7, about shaft 3, said gummer and creaser may be set nearer to or farther from blade 5 and gummer 6, to accommodate different lengths of 120 envelopes, and table 63 may be adjusted about shaft 15 to correspond therewith. It will be observed that creaser table 67 is located diametrically opposite table 63 for coaction with creaser 8 during its next suc- 125 130

ceeding revolution. By the arrangement of creaser table 63 being adjustable circumferentially of cylinder 10 the mutilation of said cylinder face is obviated. It will be observed that creaser 8 is located within circle 9 a distance equal to the projection of the coacting portion of table 63 outwardly from cylinder 10.

For receiving the envelop from cylinder 10 and ironing down the bottom flap, cylinder 17 is provided. Said cylinder has diametrically oppositely disposed clips, as 19 for receiving and gripping the bottom flap end of the envelop, as that end is delivered thereto by clip 11 or clip 12 of cylinder 10. Said clip 19 is fixed to rock shaft 68 pivoted in cylinder 17 and protrudes through an opening in the rim of said cylinder. Also fixed to rock shaft 68 is arm 69 carrying roll 70 for engagement with fixed cam 71. Spring 72 is efficient for urging roll 70 to engagement with said cam.

The operation of my improved mechanism is as follows: An envelop blank 54, having its side flaps 51 and 52 previously folded and gummed, is delivered, bottom flap 50 leading, by feed rolls 13 and 14 over the lower face of guide plate 16 in suitable timing. Just previous to the passage of the leading end of said blank over pocket 23 in plate 16, finger 22 will be lifted by the passage of roll 34 into the depression of cam 32 and said leading end of blank 54 will pass freely under said finger, Fig. 2. Roll 34 will then promptly pass to the high part of cam 32 and finger 22 will engage the face of blank 54 thereby holding pawl 25 out of engaging relation with abutment 26 of cam 27. In the meantime frame 2 has been revolving in clockwise direction about the axis of shaft 3 and cam roll 39 of gummer 6 will pass under and lift said cam 27, Fig. 3. The leading end of the envelop blank now passes downwardly over the raised end of clip 11 on cylinder 10, and blade 5, pivotally mounted on frame 2, is rotated clockwise on its axis by the engagement of roll 55 with the horn of cam 56, whereby said blade is caused to tuck flap 50 under clip 11, Fig. 5. Roll 60 then passes to the low part of cam 61 and clip 11 closes onto the folded and now leading end of the blank. At the same time roll 55 drops off the horn of cam 56 and blade 5 is withdrawn from engagement with the blank under clip 11 and leaves that blank in the grip of said clip, Fig. 6.

The continued rotation of cylinder 10 and of the coacting members on shaft 3 will presently bring the mechanism to the position of Fig. 7, wherein seal flap 53 is being creased by creaser 8 and groove 64 of table 63. The rearward end of said seal flap extends upwardly past gummer 7. Upon the passage of roll 39 from engagement with cam 27 that cam will return against stop

pin 29 but because of the presence of blank 54 between plate 16 and finger 22 pawl 25 will be unable to lock said cam. Therefore roll 43 of gummer 7 will engage and raise said cam a second time and gummer 7 will remain in its outward and operative position ready to gum seal flap 53. The continued movement of the mechanism will presently cause said gummer to press the seal flap against cylinder 10 and deposit gum upon said flap.

Cylinder 10 continuing its rotation in anti-clockwise direction, with clip 11 thereof holding folded bottom flap 50 against the face of said cylinder, presently reaches the position of Fig. 8, where roll 60 of arm 59 of said clip encounters a high portion of fixed cam 61 and said clip is raised from engagement with the envelop. Just before said clip releases its hold, roll 70 of arm 69 of clip 19 on cylinder 17 passes to a low part of fixed cam 71 and said clip 19 grips the envelop to the face of cylinder 17. As said envelop passes between cylinders 10 and 17, bottom flap 50 is ironed down against the gummed portion of side flaps 51 and 52.

Cylinder 17 continuing its rotation in clockwise direction, conveys the completed envelop away from cylinder 10 and may deliver it by means, not shown, to a suitable receptacle, not shown.

It will be understood that clips 11 and 19 are in different planes parallel with the view of Fig. 8 for instance, so that they may pass each other without interference. 100

I claim:

1. In an envelop machine the combination of a rotating cylinder having a clip thereon, means for raising and lowering said clip relatively to the periphery of said cylinder, a rotating frame contiguous to said cylinder, said frame having movably mounted thereon a flap folding blade, means for delivering an envelop blank with a flap there-of leading between said blade and said clip, means for advancing said blade outwardly from the axis of rotation of said frame and at the same time in the direction of rotation of said frame for coaction with said clip when said clip is in its raised position, for folding said flap under said clip, and for retracting said blade when said clip is lowered to grip the folded flap against the periphery of the cylinder, and means for timing said frame and cylinder. 120

2. In an envelop machine the combination of a rotating cylinder having a clip thereon, means for raising and lowering said clip relatively to the periphery of said cylinder, a rotating frame contiguous to said cylinder, said frame having pivotally mounted thereon a flap folding blade, means for delivering an envelop blank with a flap there-of leading between said blade and said clip, means for swinging said blade outwardly 130

from the axis of and in the direction of rotation of said frame for coaction with said clip when said clip is in its raised position, for folding said flap under said clip, and for 5 retracting said blade when said clip is lowered to grip the folded flap against the periphery of the cylinder, and means for timing said frame and cylinder.

3. In an envelop machine the combination 10 of a rotating cylinder having means thereon for gripping an envelop blank, a rotating frame contiguous to said cylinder, a guide plate for the envelop blank, a gummer movably mounted on said frame for coaction 15 with said cylinder for gumming said blank, means for delivering an envelop blank to the gripping means on said cylinder, means for moving said gummer out of coacting relation with said cylinder in the absence of 20 an envelop blank on said guide plate and for maintaining said gummer in said coacting relation in the presence of a blank on said guide plate, and means for timing said frame and cylinder.

25 4. In an envelop machine the combination of a rotating cylinder having means thereon for gripping an envelop blank, a rotating frame contiguous to said cylinder, a guide plate for the envelop blank, a gummer movably mounted on said frame for coaction 30 with said cylinder for gumming said blank, means for delivering an envelop blank to the gripping means on said cylinder, a gummer cam pivoted on a fixed axis extraneous 35 to the axis of said frame, an abutment on said cam, means carried by said gummer for engagement with said cam, means interposed between said guide plate and said cam and governed by the presence or absence of 40 a blank on said plate for permitting said cam to be swung on its pivot or for locking said cam against swinging, respectively, said 45 gummer cam being efficient in its locked condition for withdrawing said gummer from coacting relation with said cylinder and said gummer being efficient to maintain coacting relation with said cylinder and against the pressure of said cam in its unlocked condition, and means for timing said 50 frame and cylinder.

5. In an envelop machine the combination 55 of a rotating cylinder having means thereon for gripping an envelop blank, a rotating frame contiguous to said cylinder, a guide plate for the envelop blank, a gummer movably mounted on said frame for coaction 60 with said cylinder for gumming said blank, means for delivering an envelop blank to the gripping means on said cylinder, a gummer cam pivoted on a fixed axis extraneous to the axis of said frame, means carried by said gummer for engagement with said cam, a cam mounted coaxially 65 with and fixed to said frame, a finger pivotally mounted contiguous to said guide

plate and adapted to swing across the path of the blank on said plate, means carried by said finger and adapted to engage said gummer cam for locking said cam against movement, means interposed between said frame cam and gummer cam locking means for moving, from said cam, said finger out of the path of the blank and said locking means out of engaging relation with said gummer cam and for subsequently moving said finger, 70 in the presence of a blank on said plate, against said blank, whereby said locking means is maintained out of engaging relation with said gummer cam, or, in the absence of a blank, for moving said finger across the 75 path of the blank and said locking means into engaging relation with said gummer cam, said gummer cam being efficient in its locked condition for withdrawing said gummer from coacting relation with said cylinder 80 and said gummer being efficient to maintain its coacting relation with said cylinder and against the pressure of said cam in its unlocked condition, and means for timing said frame and cylinder.

90 6. In an envelop machine the combination of a rotating cylinder having means thereon for gripping an envelop blank, a rotating frame contiguous to said cylinder, a guide plate for the envelop blank, a gummer movably mounted on said frame for coaction 95 with said cylinder for gumming said blank, means for delivering an envelop blank to the gripping means on said cylinder, a gummer cam pivoted on a fixed axis extraneous to the 100 axis of said frame, an abutment on said cam, means carried by said gummer for engagement with said cam, a cam mounted coaxially with and fixed to said frame, a finger pivotally mounted contiguous to said guide plate 105 and adapted to swing across the path of the blank on said plate, a pawl carried by said finger and adapted to engage the abutment of said gummer cam for locking said cam against movement, means interposed between 110 said frame cam and said pawl for moving, from said cam, said finger out of the path of the blank and said pawl out of engaging relation with said abutment and for subsequently moving said finger, in the presence of a blank on said plate, against said 115 blank, whereby said pawl is maintained out of engaging relation with said abutment, or, in the absence of a blank, for moving said finger across the path of the blank and said pawl into engaging relation with said abutment, said gummer cam being efficient in its 120 locked condition for withdrawing said gummer from coacting relation with said cylinder and said gummer being efficient to maintain its coacting relation with said cylinder and against the pressure of said cam in its unlocked condition, and means for timing said frame and cylinder.

125 7. In an envelop machine the combination 130

of a rotating cylinder having a clip thereon, means for raising and lowering said clip relatively to the periphery of said cylinder, a rotating frame contiguous to said cylinder, 5 said frame having movably mounted thereon a flap folding blade for coaction with said clip and a gummer for coaction with said cylinder, a guide plate for the envelop blank, means for delivering an envelop blank with 10 a flap thereof leading between said gummer and blade on the one hand and said clip on the other hand, means for moving said gummer out of coacting relation with said cylinder in the absence of an envelop blank on 15 said guide plate and for maintaining said gummer in said coacting relation in the presence of a blank on said guide plate, means for advancing said blade outwardly from the axis of rotation of said frame and at the 20 same time in the direction of rotation of said frame for coaction with said clip when said clip is in its raised position, for folding said flap under said clip, and for retracting said blade when said clip is lowered to grip 25 the folded flap against the periphery of the cylinder, and means for timing said frame and cylinder.

8. In an envelop machine the combination of a rotating cylinder having means thereon 30 for gripping a blank, a creaser table pivoted coaxially with said cylinder and circumferentially adjustable on the periphery of said cylinder, a rotating frame contiguous to said cylinder, a creaser mounted on said 35 frame and having an edge adapted for coaction with the creaser table on said cylinder, and means for timing said frame and cylinder, said frame being rotatively adjustable about its axis of rotation to bring its creaser 40 into coacting relation with any adjusted position of said table.

9. In an envelop machine the combination of a rotating cylinder having means thereon 45 for gripping a blank, a creaser table pivoted coaxially with said cylinder and circumferentially adjustable over the unbroken periphery of said cylinder, a rotating frame contiguous to said cylinder, a creaser mounted on said frame for coaction with the creaser

table on said cylinder, and means for timing 50 said frame and cylinder, said frame being rotatively adjustable about its axis of rotation, and said creaser rotating in a circular path lying at its nearest point a distance from the cylinder equal to the height of the coacting 55 portion of said table from said cylinder.

10. In an envelop machine the combination of a rotating cylinder having means thereon for gripping an envelop blank, a creaser table carried on the peripheral surface of 60 said cylinder and circumferentially adjustable thereover, a rotating frame contiguous to said cylinder, a creaser mounted on said frame having an edge adapted for coaction with the creaser table on said cylinder, and 65 means for timing said frame and cylinder, said frame being rotatively adjustable to bring its creaser into coacting relation with any adjusted position of said table, the coacting edge of said creaser rotating in a 70 circular path lying, at its nearest point, a distance from the cylinder equal to the height of the coacting portion of said table from said cylinder.

11. In an envelop machine the combination 75 of a rotating cylinder having means thereon for gripping an envelop blank, a creaser table carried on an unbroken portion of the peripheral surface of said cylinder and circumferentially adjustable over said 80 unbroken portion, a rotating frame contiguous to said cylinder, a creaser mounted on said frame having an edge adapted for coaction with the creaser table on said cylinder, and means for timing said frame and 85 cylinder, said frame being rotatively adjustable to bring its creaser into coacting relation with any adjusted position of said table, the coacting edge of said creaser rotating in a circular path lying, at its nearest 90 point, a distance from the cylinder equal to the height of the coacting portion of said table from said cylinder.

Signed at New York, borough of Manhattan, in the county of New York and 95 State of New York this 7th day of Nov., 1917.

ABRAHAM NOVICK.
